CLAIM

The ornamental design for a brassiere for nursing women, as shown and described.

DESCRIPTION

FIG. 1 is a front, left side, top perspective view of a brassiere for nursing women showing my new design;

FIG. 2 is a rear, right side, top perspective view thereof;

FIG. 3 is a front elevational view thereof;

FIG. 4 is a rear elevational view thereof;

FIG. 5 is a left side elevational view thereof;

FIG. 6 is a right, side elevational view thereof;

FIG. 7 is a top plan view thereof;

FIG. 8 is a bottom plan view thereof;

FIG. 9 is a front elevational view thereof with the brassiere disposed at its fully opened position;

FIG. 10 is a rear elevational view thereof with the brassiere disposed at its fully opened position;

FIG. 11 is a front elevational view thereof as the brassiere would be worn by a woman; and,

FIG. 12 is a front elevational view thereof as the brassiere would be worn by a woman and wherein breast pumps could be accommodated therein.

The broken lines in the drawings depict portions of the brassiere for nursing women and environment that form no part of the claimed design.
